UNITED STATES PATENT OFFICE.

HARRISON S. RIDER, OF DEODATE, PENNSYLVANIA.

SEALING DEVICE FOR JAR-CAPS.

1,132,121.

Specification of Letters Patent. Patented Mar. 16, 1915.

Application filed June 16, 1914. Serial No. 845,479.

To all whom it may concern:

Be it known that I, HARRISON S. RIDER, citizen of the United States, residing at Deodate, in the county of Dauphin and State of Pennsylvania, have invented certain new and useful Improvements in Sealing Devices for Jar-Caps, of which the following is a specification.

This invention relates to an improved device for sealing jar closures and is especially designed for use in connection with circular metallic caps which are adapted to have screw threaded engagement with suitable jars, the invention having as its primary object to provide an implement of this character which may readily be operatively connected with the cap and rotated thereon to press the terminal radial flange formed at the outer extremity of the side wall of the cap into engagement with the gasket commonly interposed between said flange and the body portion of the jar, to thus provide an air-tight closure.

The invention has as a still further object to provide a device of this character which will be simple in construction and which may be used upon any conventional type of circular metallic jar cap as now on the market.

With these and other objects in view, my invention will be more fully described illustrated in the accompanying drawings, and then specifically pointed out in the claims which are attached to and form a part of this application.

In the accompanying drawings:—Figure 1 is a perspective view showing the manner in which my improved sealing device is applied for use, the portion of the jar shown being conventionally illustrated. Fig. 2 is a transverse sectional view showing the device applied and particularly illustrating the manner in which the disk carried thereby is disposed to engage the terminal flange of the jar cap, and Fig. 3 is a detail perspective view of the device.

Corresponding and like parts are referred to in the following description and indicated in all the views of the drawings by the same reference characters.

For the purposes of convenience, I have illustrated in the drawings, the manner in which the improved device is applied and have conventionally shown a jar 10 which is provided with the circular neck 11 adapted to have screw threaded engagement with

the cap 12, the side wall of the cap being indicated at 13, which wall as usual, is formed with the terminal radially extending flange 14, said flange being arranged to engage against the gasket 15 which encircles the neck of the jar. As is well known, the ordinary jar cap of this character is made of soft metal and is thus liable to accidental injury, and that any mutilation of the flange 14 such as would interrupt the flat bearing surface of said flange arranged to contact with the gasket 15 will render the cap of no further use since the imperfect joint which would then be formed by the flange between the gasket 15 and the cap would permit air to gain access to the interior of the jar to effect the fermentation or spoiling of the contents thereof. The present invention, therefore, seeks to provide a device by which the flange 14 of the jar cap may be brought into close and interrupted engagement with the gasket 15 carried by the jar, and so constructed that by rotating the device upon the cap, any inequalities in the bearing surface of said flange such as might have been brought about through the injury thereof may be rolled out so that the flange may form a perfect joint between the gasket and the cap.

Coming now to more particularly describe the invention, the body portion 16 thereof includes a substantially semi-circular preferably concavo convex bearing flange 17 which presents the inner concave face 18. Formed on the upper edge of the bearing flange 17 and connecting the extremities thereof, is a transversely extending arm 19 and intersecting the arm 19 midway the ends thereof and extending at substantially right angles to said arm is an arm 20, the arm 20 being joined at its inner extremity, with the upper edge of the bearing flange 17 substantially midway the ends of said flange.

The arm 20, adjacent to its outer extremity is obliquely directed longitudinally as shown at 21 to extend away from the bearing flange 17 upon the contiguous side of said arm and the adjacent terminal 22 thereof is thence again directed longitudinally in reverse relation to extend obliquely toward the free lower edge of said flange. Mounted for rotation upon a suitable pin 23 and arranged adjacent the inner face of the inwardly directed terminal 22 of the arm 20 is a disk 24, the periphery of which is beveled to provide an inclined face 25 slop-

ing away from the adjacent terminal of the arm 20.

In Figs. 1 and 2 of the drawings, I have shown the manner in which the device is applied in use and it will be observed that the side wall of the cap 12 is embraced by the bearing flange 17 and by the arm 20, the bearing flange being of a width slightly greater than the side wall of the cap and bearing at its free outer edge upon the flange 14 thereof, while the obliquely directed portion 21 of the arm 20 is disposed to extend over the upper edge of the cap opposite the bearing flange 17 with the disk 24 bearing by its beveled face 25 upon the adjacent portion of the peripheral edge of said flange. It will be observed that owing to the angular disposition of the terminal 23 of the arm 20, that when downward pressure is exerted upon the body portion 16, the disk 24 will be caused to bear downwardly and inwardly upon the peripheral edge of the flange 14 to not only thereby force the side wall of the cap into secure engagement with the neck of the jar 10, but the flange 14 at its outer edge will also be brought into firm engagement with the gasket 15.

In practical use, it is intended that after the cap 12 of the jar has been applied thereto in the usual manner, that the device shall be placed upon the cap as shown in Figs. 1 and 2 of the drawings, and then rotated thereon, downward pressure being exerted upon the body portion 16 as the device is rotated. It will be clear that the disk 24 may be passed over the flange 14 throughout its entire circumference as many times as desired and the inclined face 25 of said disk upon engaging the peripheral edge of the flange will smooth out or roll out any inequalities therein which may have been brought about through accidental injury to the flange, to provide a smooth, uninterrupted bearing surface upon the inner face thereof to contact with the gasket 15, and will also bend the peripheral margin of said flange downwardly and inwardly toward the neck of the jar to securely engage the gasket arranged thereon. Attention is also called to the fact that while the disk 24 is arranged to contact with the flange 14 at a substantially obtuse angle thereto, the bearing flange 17 is arranged to contact with the flange at substantially right angles thereto, the disk having a tendency to force said flange downwardly and inwardly as above stated, toward the neck of the jar, while the bearing flange 17 is disposed to force said flange downwardly toward the body portion of the jar when pressure is applied thereto, to bring said flange throughout its entire width, into contact with the gasket 15. Thus, when the device is rotated about the cap 12, the flange 14 of said cap will not only be forced downwardly to bear flatly against the gasket

15, but will be turned downwardly and inwardly at its peripheral margin to engage said gasket. The effective sealing of the jar is thus secured and it will be noted that the device is exceedingly simple in construction and may be readily applied and used. Attention is also called to the fact that when downward pressure is exerted upon the body portion 16 in the practical use of the device, that the free edge of the bearing flange 17 which rests upon the flange 14 of the cap 12 will be caused to coact with the disk 24 to smooth out any inequalities in the surface of the flange 14, such as slight depressions or upwardly projecting portions in said flange to thus insure the provision of an uninterrupted flat bearing surface upon the inner face of said flange, such surface being disposed to contact with the gasket 14 or with the body portion of the jar proper as the case may be. However, it will be clear that my improved device may be employed with equal effectiveness upon jar caps which have not previously been applied in use, and have not therefore, been exposed to the possibility of mutilation, but the construction which I provide is especially advantageous since by the use of the device, jar caps which have been used several times and which may have become mutilated, may be repeatedly employed without the possibility of the contents of the vessels closed by said caps fermenting or spoiling, due to the inefficient sealing of the vessels thereby.

It will therefore be seen that I provide a very efficient construction for the purpose set forth and that the complete device may be readily manufactured in various sizes to accommodate the diameters or the various heights of different jar caps.

Having thus described my invention, what I claim and desire to secure by Letters Patent is:—

1. A device of the character described including a body portion adapted to engage a jar cap to be rotated thereon, said body portion being integrally formed and including a substantially semi-circular bearing flange, an arm extending from one edge of said flange to project laterally upon one side of the concave face thereof, said arm being obliquely directed longitudinally adjacent its outer extremity and the terminal thereof thence obliquely directed longitudinally in reverse relation to said first mentioned obliquely directed portion to extend inwardly toward the said flange, and a disk mounted for rotation upon the said terminal of the arm, said disk being beveled upon its periphery inwardly toward said flange and arranged to contact with the peripheral margin of the terminal flange of the jar cap.

2. A device of the character described adapted to engage a jar cap to be rotated thereon and provided with coacting mem-

bers, one including a body portion being disposed to engage the terminal peripheral flange of said cap at substantially right angles thereto, and the other to engage the 5 said flange at a substantially obtuse angle thereto.

3. A device of the character described adapted to embrace a jar cap to be rotated thereon and including a semi-circular flange 10 disposed to confront the side wall of the cap, the said flange having a transversely extending arm formed on one edge thereof connecting the extremities of the flange and being provided with a second arm intersecting 15 said first mentioned arm and connected with the said flange between the ends thereof, and a member carried by the free extremity of said second mentioned arm and disposed to engage the terminal peripheral 20 flange of said cap.

4. As a new article of manufacture, a jar cap sealing device integrally formed from suitable sheet metal and including a flange disposed to engage the side wall of a jar 25 cap, the extremities of said flange being joined by a transversely extending arm and

connected with the flange upon one edge thereof, the said arm being intersected by a second arm connected with the flange substantially midway of its ends, and a member 30 rotatably mounted upon the free extremity of said second mentioned arm and disposed to engage the terminal peripheral flange of the jar cap to be rotated around the cap upon the said flange thereof. 35

5. A device of the character described including a substantially semi-circular flange disposed to confront the side wall of a jar cap, an arm formed on said flange and arranged to extend over the top of the cap 40 and over the side thereof, opposite said flange, and a member carried by the free extremity of said arm and disposed to engage the terminal peripheral flange of said cap, to be moved circumferentially around 45 the cap upon the said flange thereof.

In testimony whereof I affix my signature in presence of two witnesses.
